UNITED STATES PATENT OFFICE.

JAMES ALFRED KIDD, OF PETERSBURG, VIRGINIA, ASSIGNOR OF ONE-THIRD TO
STANLEY F. MASON, OF PETERSBURG, VIRGINIA.

ROTARY VALVE ATTACHMENT.

Continuation of application Serial No. 490,371, filed August 6, 1921. This application filed September 21, 1921. Serial No. 502,154.

To all whom it may concern:

Be it known that I, JAMES A. KIDD, a citizen of the United States, residing at Petersburg, in the county of Dinwiddie and State 5 of Virginia, have invented a new and useful Rotary Valve Attachment, of which the following is a specification.

The present invention aims to provide novel means whereby, when the valve stem 10 of an internal combustion engine is reciprocated, rotary motion will be imparted to the valve for the purpose of grinding the valve, the valve spring being anti-frictionally supported, this application being a continuation 15 of my prior application for Letters Patent on a rotary valve attachment, Serial No. 490,371, filed on August 6, 1921.

It is within the province of the disclosure 20 to improve generally and to enhance the utility of devices of that type to which the invention appertains.

With the above and other objects in view, which will appear as the description proceeds, the invention resides in the combination 25 and arrangement of parts and in the details of construction hereinafter described and claimed, it being understood that, within the scope of what is claimed, changes in the precise embodiment of the invention 30 shown can be made without departing from the spirit of the invention.

In the accompanying drawings:

Figure 1 shows in elevation, an engine 35 equipped with the device forming the subject matter of this application; Figure 2 is a section on the line 2—2 of Figure 1; Figure 3 is a section on the line 3—3 of Figure 2; and Figure 4 is a fragmental plan showing a portion of the engine frame and the carrier 40 whereon the actuating pawls are mounted.

The numeral 1 designates the frame of an internal combustion engine, the same having a valve seat 2. A bearing 3 is mounted in 45 the frame 1 and the lower portion of the frame carries a bearing boss 4. A valve 5 cooperates with the seat 2 and is carried by a stem 6 mounted to reciprocate in the bearing 3. The stem 6 cooperates with a tappet 7 mounted for reciprocation in the boss 4. The tappet 7 is actuated by a cam 8 on a cam shaft 9. A spring 10 surrounds a portion of the stem 6, and, abutting against the frame 1 and cooperating with the stem, con-

stitutes means for closing the valve 5 on the 55 seat 2. The construction above described is common and may be changed depending upon the make of the engine, without departing from the spirit of the invention. No novelty is claimed for the parts above 60 described, saving in so far as they may cooperate with parts hereinafter set forth.

A ratchet wheel 11 is secured to the stem 6 and is provided on its lower surface with radial teeth 12. The teeth 12 of adjacent 65 ratchet wheels slope in opposite directions, as shown in Figure 1. The ratchet wheel 11 has a neck 14 attached by a securing element 15 to the stem 6. A washer 16 surrounds the neck 14 of the ratchet wheel and holds the 70 securing element 15 in place against endwise movement. The washer 16 is provided with an annular recess 17, receiving the lower end of the spring 10. The washer 16 and the ratchet wheel 11 are provided with 75 cooperating ball races 44, receiving balls 45. The balls, obviously, constitute an anti-friction bearing for the spring 10 and facilitates the rotation of the valve 5.

The device embodies a trough-shaped carrier 18 including inner and outer walls. The carrier 18 is supported on the lower portion of the frame 1 and abuts against the bosses 4. The inner wall of the carrier 18 has bendable fingers 19 engaged around the 85 outermost bosses 4, as shown in Figure 4, to hold the carrier 18 in place.

Pairs of oppositely extended pawls 20 are provided, the lower ends of the pawls being disposed between the walls of the carrier 18, 90 and being mounted thereon, for vertical swinging movement on pivot elements 21. The upper ends of the pawls 20 of each pair cooperate with the teeth 12 of adjoining ratchet wheels 11. The resilient means for holding the pawls 20 engaged with the teeth 12 of the ratchet wheels 11 may be of any desired sort. If preferred, a bowed spring 25 may be located between the walls of the carrier 18, the spring having reversely 100 curved ends 26, bearing on the under edges of the pawls 20, as shown in Figure 1, there being one spring for each pair of pawls.

The operation of the device will be understood readily from the foregoing, but it may 105 be stated briefly that when the stems 6 move upwardly, the pawls 20 will click over the ratchet wheels 11, whereas, when the stems

6 move downwardly, the pawls 20 will impart rotation to the stems 6 and consequently to the valves 5, through the instrumentality of the ratchet wheels 11. When the valves 5 are rotated, as aforesaid, they will be ground, and be kept clear of carbon.

What is claimed is:—

1. The combination with the crank case of an engine, stems mounted for reciprocation and for rotation, and valves on the stems, of ratchet wheels on the stems and having oppositely slanting teeth; oppositely extended pawls cooperating with the teeth of the ratchet wheels; a single resiliently supported spring coacting with both pawls and with the crank case to hold said pawls in operative relation to the ratchet wheels; and means for mounting the pawls for pivotal movement.
2. In a device of the class described, an engine having bosses; valves mounted for reciprocation and for rotation; operating means for the valves, said means being mounted in the bosses, ratchet wheels carried by the stems of said valves; a carrier having means for engaging certain of the bosses; and pawls pivoted to the carrier and coacting with the ratchet wheels to rotate the valves.
3. As an article of manufacture, for use in the making of a valve rotator, a trough-shaped carrier including walls, one wall be-

ing provided with bendable fingers; a pawl pivotally mounted between the walls; and an actuating spring for the pawl, the actuating spring being housed between the walls.

4. The combination with the crank case of an engine, stems mounted for reciprocation and for rotation and valves on the stems, of ratchet wheels on the stems and provided with necks, the ratchet wheels having oppositely slanting teeth, securing elements mounted in the necks and engaging the stems, washers about the stems and cooperating with the securing elements to prevent endwise movement thereof, anti-friction elements interposed between the washers and the ratchet wheels, springs cooperating with the washers to close the valves oppositely extended pawls coacting with the teeth of the ratchet wheels, a single resiliently supported spring coacting with both pawls and with the crank case to hold said pawls in operative relation to the ratchet wheels, and means for mounting the pawls for pivotal movement.

In testimony that I claim the foregoing as my own, I have hereto affixed my signature in the presence of two witnesses.

JAMES ALFRED KIDD.
